UNITED STATES PATENT OFFICE.

WILLIAM A. READE, OF CLEVELAND, OHIO, ASSIGNOR TO THE LUDLOW TYPOGRAPH COMPANY, OF CLEVELAND, OHIO, A CORPORATION OF MAINE.

TYPOGRAPH.

1,146,277.

Specification of Letters Patent.

Patented July 13, 1915.

Application filed August 15, 1910. Serial No. 577,305.

To all whom it may concern:

Be it known that I, WILLIAM A. READE, a citizen of the United States, and a resident of Cleveland, county of Cuyahoga, and 5 State of Ohio, have invented a new and useful Improvement in Typographs, of which the following is a specification, the principle of the invention being herein explained and the best mode in which I have 10 contemplated applying that principle, so as to distinguish it from other inventions.

The general form of the typograph to which the present invention relates is that disclosed in U. S. Patent No. 856,539, issued 15 to Washington I. Ludlow, June 11, 1907. In such "Ludlow" typograph the means for casting the type line comprise a plurality of matrix bars movably resting upon a suitable support which is provided with a trans- 20 verse casting slot over which such bars are adapted to be collected or "composed", so as to aline the duplicate series of matrices on their under edges as desired.

By the present invention I contemplate 25 the provision of improved justifying means for use in a typograph of the kind just referred to, together with various modifications in the construction of the matrix bars; as also the improvement of certain details 30 of the mechanism constituting the composer means that assist in the arrangement and retention of the bars in varied relation to each other for casting linotype therefrom.

To the accomplishment of the foregoing 35 and related ends, said invention then consists of the means hereinafter fully described and particularly pointed out in the claims.

The annexed drawings and the following 40 description set forth in detail certain mechanism embodying the invention, such disclosed means constituting, however, but several of the various mechanical forms in which the principle of the invention may 45 be used.

In said annexed drawings:—Figure 1 is a 50 plan view of an assembled body of matrix bars embodying my present improved construction, together with a detail of the com- 55 poser frame in position over such bars; Fig. 2 is a vertical section taken longitudinally of such body of bars and showing, in addition to the composer frame, certain other co- 60 operative parts; Fig. 3 is the same as Fig. 2

but with certain parts differently arranged; 55 Fig. 4 is a broken plan view of the composing mechanism with the composer frame omitted, but including the matrix bars and showing the method of justifying a line; Fig. 5 is a broken elevational view of one 60 kind of matrix bar; Figs. 6 and 7 are similarly broken top and bottom plan views of such bar, respectively; Fig. 8 is a bottom plan view of another kind of matrix bar designed for use in connection with bars of 65 the kind illustrated in the two preceding figures; Fig. 9 shows a construction of bar modified as to the locking feature whereby the bars are held in their assembled condition; Fig. 10 illustrates such modified bar 70 with correspondingly modified coöperating parts; Fig. 11 shows a body of bars in assembled, but inverted position; Figs. 12 and 13 show yet another construction of bar; and Fig. 14 is a plan view of the machine 75 top.

The composing mechanism proper, where- 80 of certain portions are necessarily shown in connection with the improvements constitut- 85 ing the present invention, forms the sub- 90 ject matter of a separate joint application of myself and George O. Cromwell, filed May 6, 1910, Serial No. 559,835. So far as present purposes are concerned, however, 95 such mechanism may be regarded as sub- 100 stantially the same as that disclosed in the patent previously referred to; in other words, such mechanism comprises in effect an open frame D of general rectangular form that is slidably, or otherwise mounted 90 upon the bed A of the machine, so as to be movable across the bars, when the latter are disposed in the trough in such bed provided for their reception. This frame typifies, in general, any form of coöperating means 95 adapted to secure the bars in selected lon- 105 gitudinal position in such trough with the matrices on their under faces located over the casting slot a in the bottom of the trough.

The casting box or mold B is designed to fit snugly in such slot a and its upper face then lies flush with the bottom of the trough, so that the movement of the bars there- 100 across, is in no wise interfered with. The 105 mold is, of course, formed with an opening or slot in which the slug is actually cast, and it is specifically over this opening,

rather than over the general opening in the bottom of the trough that the matrices on the bars require to be assembled. The rear wall α' of the trough may then be regarded as an abutment at one end of such casting slot, while an adjustable block α^2 in the front wall α^3 , or such wall itself in the retracted position of this block, constitutes an oppositely facing abutment at the other end of such slot.

The general supporting frame for the bed plate or table A, that thus serves as a support for the matrix bars C is not illustrated, but such frame, it may be explained, is utilized to support not only the casting mold B, but also the other parts of the casting mechanism required for the forming of slugs or lines-of-type in such mold. Of such other parts the only one appearing is the nozzle or spout B' of the casting pot through which the molten metal is forced into the mold after the bars have been properly assembled thereover to form a line in intaglio. Such casting-pot spout is terminally closed by a squirt plate b that is designed to be brought directly against the under side of the mold when desired, and then be removed so as to permit such mold to be lowered from the bed of the machine in order that the slug may be ejected therefrom, and such further operations performed on the slug as are necessary preliminarily to its removal to the galley and its setting up in the press form.

The matrix bars C, I make, in the main, of the laterally tapered form shown in Figs. 6 and 7, from an inspection of which it will be seen that such taper is continuous from one end to the other of the bar. The matrices c are then struck in, or otherwise formed, on the lower edge of the bar, regarding the latter as it rests in the trough, while in its upper edge are provided transverse grooves c' corresponding in position with such matrices, and in connection with the grooves a series of characters that likewise correspond with such matrices, and preferably placed directly thereover for reasons that will be explained presently. These bars C are disposed on a suitable support provided with a transverse casting slot, and with oppositely facing abutments adjacent to such slot, said bars being arranged with their tapered ends alternating with their thick ends, whereby the several bars are maintained in a line substantially at right angles to such casting slot, whatever variation may be made in their longitudinal position relatively to such slot. Although adjacent bars will thus be seen to bear similar series of matrices, the order of such matrices will obviously be reversed. Preferably, the aforesaid support for the bars consists of a trough in the bed-plate A, such trough being either open at its ends, or of

such length as to permit of the free longitudinal movement of the bars therein, after the fashion hereinafter set forth. The lateral walls of such trough, or projections integral therewith, constitute the oppositely facing abutments between which the bars are assembled. In the specific construction illustrated, moreover, the casting slot is not formed directly in the bottom of this trough, but in a supplemental casting box which is adapted to fit in a suitable opening in such trough bottom, and when thus fitted, to lie substantially flush with the surface of such trough. Furthermore, such matrices terminate short of the thin ends of the bars (see Fig. 7), whereby the latter are adapted, when overlapping, to form a blank space of adjustable width. The upper edges of such thin ends of the bars are cut away as shown at c^2 , (Fig. 5) to a depth equal to that of the grooves c' previously referred to as being formed in its upper edge. In addition to these grooves, each matrix bar is provided on this same upper edge with a pin c^4 or equivalent projection, that is centrally disposed with respect to the series of matrices on its under edge or otherwise bears a fixed relation to the same. Not only are the lower edges of the bars blank at their ends, but a limited number of blank spaces c^5 are left among the matrices c, being so located along the bar as to provide an assortment of widths. One such blank c^5 , moreover is located directly below the pin c^4 on the bar's upper edge, and the arrangement of the others is such that they register with those on adjacent bars, (see Fig. 11), when the two bars are brought up with their ends even, despite the reversed order in which the regular series of characters appear on such bar. This materially facilitates "quadding" or spacing out partial lines. Aside from the regular set of tapered matrix bars, which thus carry matrices constituting a font of type, other bars C' (Fig. 8), with parallel sides are provided to bear matrices of special characters of various kinds that require to be used only at rare intervals. These may obviously be inserted at any place in the body of tapered bars, without disturbing the squaring up of such body of bars as a whole.

Of the composer frame D, the only detail requiring to be noted in the present connection is the series of equidistantly spaced teeth F that extend inwardly from the rear side of such frame in a transverse direction with respect to the matrix bars, or in other words, parallel with the casting slot b' in the mold B. There are as many of these teeth F as there are matrices upon the respective matrix bars C carrying the normal font, the disposition of these teeth being such that when the centrally mounted pin c^4 on any bar is inserted in the slot f between the appropriate teeth, a particular matrix on the

under side of such bar will be positioned directly over the opening in the mold.

To indicate which slot is to be selected to thus bring any desired matrix over the mold, 5 the teeth are conveniently provided with designating characters as shown in Fig. 1. In view, however, of the reversal of alternate matrix bars in the normal font, a double series of designating characters requires 10 to be provided upon the teeth, one of which series is adapted for use with matrix bars having their thick ends disposed toward the right end of the trough, the other for use with the bars which have their thick ends 15 disposed toward the left of such trough.

A supplementary series of characters may be used to indicate the position of the matrices on the upper side of the supernumerary bars C' that have parallel sides and bear 20 special matrices, as heretofore described. It will be understood, of course, that of the arrangement of the characters on the tapered bars, those requiring the largest width will be disposed nearest the thick end of the bar, while those requiring less width will be disposed nearest the other, or thin, end of the bar. Despite this requirement, there will be sufficient opportunity for selection of position to permit the location of those matrices, which have to be most frequently 30 employed, near the center of the bar. Accordingly only relatively short longitudinal movements will be required for the placing of the bars so as to bring the characters most 35 frequently used, over the casting slot; in other words, it will only be relatively rarely that a bar will require to be displaced its full length to bring a character, either at its thick end or thin end, over such slot.

40 Two teeth F of the composer frame located on either side of the central line of the frame, and hence occupying a corresponding relation to the opening in the mold, are considerably heavier than the remaining teeth, 45 as shown in Figs. 2 and 3; in fact each of such central teeth occupies the space that would be occupied by two of such other teeth. These teeth are formed on their under sides with splines f' adapted to enter 50 the transverse slots or grooves c' previously described as being formed in the upper edges of the several matrix bars. By making the splines and grooves to fit relatively closely, the alinement of the matrices on the under 55 faces of the bars immediately below such two teeth F can be made quite accurate. In other words, the engagement of the pins c' on the upper edges of the bars with the slots between the teeth of the frame serves, in a 60 sense, merely as an initial means of locating the bars, their final adjustment being effected by engagement of these splines with the grooves on such edges, as will be readily understood.

65 The inner edges of the upper faces of the

two teeth F in question are beveled so as to incline downwardly to the opening between the teeth, which forms a "sight" of a width substantially equal to the width of a space between two slots c' on the bars' upper edges. 70 Since on these spaces, characters c' corresponding with the matrices located immediately therebeneath are provided, it will be seen that visual composition is possible, these characters appearing in the same assembled 75 form as do the matrices on the under faces of the several selected bars. To assist in the composition of the line, the beveled faces of the two teeth in question are respectively provided with a scale f² in ems corresponding 80 with the length of the line to be cast, and with a central line f³ to assist in the composing of captions or short lines. The em scale is preferably carried on a removable plate so that a corresponding scale may 85 be substituted for whatever length of line is to be cast.

By the foregoing arrangement, the operator can observe the successive placing of the matrices in casting position, and as the line 90 is thus composed, the approximate amount of space to be allowed between successive words can be determined, as also the manner in which to split or hyphenate words at the end of the line, without having to try or 95 fit. It has been previously indicated that the spaces between words are formed by the overlapping thin ends of paired bars C, and that such space can be made greater or less by varying the relative position of the bars, 100 as will be readily understood.

At the completion of the composing of a line, as shown in Fig. 4, and as may frequently happen, a small space is left over, so that it is necessary to justify the line 105 before casting the slug. This justification, in the case of the present invention, is readily and easily accomplished by simply forcing together the paired matrix bars having their thin ends overlapping to form the spaces 110 between words, since such inward movement of these bars will effect a corresponding spreading of the spaces until the entire line is filled. The amount of the movement of these bars under the pressure thus applied 115 will of course be variable, depending on the width of the space to be taken up in justifying the line.

Such inward movement of the bars in question is obtained by the use of two blocks 120 H respectively slidably mounted in either end of the trough and beyond the position occupied, even when farthest extended, by the thick ends of the matrix bars. These blocks may be operatively connected by a 125 system of levers and connecting rods (see Fig. 14) one of which levers may bear a handle or, for present purposes may be simply looked upon as directly, manually operable. This inward movement of the 130

blocks is continued until the butt ends of the bars, whose thin ends thus overlap to form spaces, are engaged, with the result previously noted, namely, that the thin ends wedge 5 apart the assembled body of bars until a line is completely justified. It will be understood, of course, that the actual amount of lateral displacement of the bars ordinarily required is very slight, but the inward pressure 10 of the blocks H serves to obtain this important adjustment. The bars thus thrown to one end or the other of the trough for use in justifying the line are, moreover, temporarily secured to the blocks H, as by a 15 silent plate h on the latter that is adapted to engage a notch c⁶ provided for this purpose at the thick end of each bar (see Fig. 5). The bars may thus be withdrawn as well as forced inwardly.

20 The modified construction of matrix bar C² illustrated in side elevation in Fig. 9 differs from the form shown in Figs. 5, 6 and 7 only as to the engaging means constituting the locking feature whereby the bars are 25 held in their assembled condition. In such modified bar, in other words, in place of transverse grooves c' in the upper edge of the bar wherewith splines f' are adapted to engage being used to thus lock the bars, the 30 latter are formed with a series of apertures or holes c⁷ and the frame D bears a special rod-like tooth d, appearing in cross section in Fig. 10, which is adapted to pass through such apertures when they are alined over 35 the casting slot, as will be the case when the bars are brought into proper position with the selected matrices over such slot. At the thin ends of the bars such perforations are replaced by an elongated slot c⁸ corresponding 40 in location and function to the cut-away portion c² of the previously described form of bar.

Still a further modification in the construction of the matrix bars is shown in 45 Figs. 12 and 13. From the first of said figures such modified bar C³ will be seen to conform in its general lateral taper with that of the bar C illustrated in Figs. 6 and 7, save that the thin end tapers more 50 abruptly or sharply, beginning at a point c⁹ so that the aforesaid thin end is very thin indeed; in fact in practice it may be brought almost to a knife edge, although it will be understood that the sharpness of such edge has 55 no significance but merely the increase in taper through such terminal portion of the bar. This increase I have found augments the wedging effect when the overlapping bars are forced together to justify a line of matrices assembled over the casting slot. The 60 manner of operation where such bars as these last described are employed, is substantially the same as before, care being merely taken not to have the slight offset 65 marking the change in taper directly over-

the casting slot since otherwise a slight opening would be left through which metal might escape and thereby form a "fin".

Other modes of applying the principle of my invention may be employed instead of 70 the one explained, change being made as regards the mechanism herein disclosed, provided the means stated by any of the following claims or the equivalent of such stated means be employed.

75 I therefore particularly point out and distinctly claim as my invention:—

1. The combination of a plurality of laterally tapered matrix bars arranged side by side, adjacent bars having their thin ends 80 oppositely directed and bearing similar series of matrices but in reverse order, such matrices terminating short of such thin ends, whereby the latter are left blank; and means adapted to secure said bars with 85 selected matrices in alinement, the thin ends of said bars being formed so as to be unaffected by said securing means, whereby such end of any bar is adapted to be moved independently of said securing means to 90 form a blank space of adjustable width in such line of matrices.

2. The combination of a plurality of laterally tapered matrix bars arranged side by side, adjacent bars having their thin ends 95 oppositely directed and bearing similar series of characters but in reverse order, such matrices terminating short of such thin ends, whereby the latter are left blank; means adapted to secure said bars with 100 selected matrices in alinement, the thin ends of said bars being formed so as to be unaffected by said securing means, whereby such end of any bar is adapted to be moved independently of said securing means to 105 form a blank space of adjustable width in such line of matrices; and means for forcing a bar with its thin end across such line, whereby a line of assembled matrices may be justified.

110 3. The combination of a plurality of laterally tapered matrix bars arranged side by side, adjacent bars having their thin ends oppositely directed and bearing similar 115 series of matrices but in reverse order, such matrices terminating short of the thin ends of the bars, whereby such thin ends are left blank; and means adapted to secure said bars with selected matrices in alinement, the thin ends of said bars being formed so as to be unaffected by said securing means, any pair of said bars being thus rendered movable independently of said securing means to cause their thin ends to overlap and thus form a blank space of adjustable width in 120 such line of matrices.

4. The combination of a plurality of laterally tapered matrix bars arranged side by side, adjacent bars having their thin ends oppositely directed and bearing similar 125

series of characters but in reverse order, such matrices terminating short of such thin ends, whereby the latter are left blank; means adapted to secure said bars with 5 selected matrices in alinement, the thin ends of said bars being formed so as to be unaffected by said securing means, and any pair of said bars being thus rendered movable independently of said securing means to 10 cause their thin ends to overlap and thus form a blank space of adjustable width in such line of matrices; and means for forcing together bars with their thin ends thus overlapping, whereby a line of assembled 15 matrices may be justified.

5. The combination with a suitable support provided with a transverse casting slot and with oppositely facing abutments adjacent to such slot; of a plurality of laterally 20 tapered matrix bars arranged side by side on said support, adjacent bars bearing similar series of characters but in reverse order, such matrices terminating short of the thin ends of said bars, whereby the latter are left 25 blank and are adapted, when overlapping, to form a space of adjustable width; and blocks longitudinally movable on said support adapted to force together bars with their thin ends thus overlapping, whereby a line of 30 matrices assembled over such casting slot may be justified.

6. The combination with a suitable support provided with a transverse casting slot and with oppositely facing abutments adjacent to such slot; of a plurality of laterally 35 tapered matrix bars arranged side by side on said support, adjacent bars bearing similar series of characters but in reverse order, such matrices terminating short of the thin 40 ends of said bars, whereby the latter are left blank and are adapted, when overlapping, to form a space of adjustable width; blocks longitudinally movable on said support adapted to force together bars with their 45 thin ends thus overlapping, whereby a line of matrices assembled over such casting slot may be justified; and means adapted to thus simultaneously actuate said blocks.

7. The combination with a suitable support 50 provided with a transverse casting slot and with oppositely facing abutments adjacent to such slot; of a plurality of laterally tapered matrix bars arranged side by side on 55 said support, adjacent bars bearing similar series of matrices but in reverse order, such 60 matrices terminating short of the thin ends of the bars, whereby such thin ends are left blank and any bar is adapted to form a space of adjustable width on a line transversely of said bars; engaging elements on 65 said bars save at their thin ends; a frame movable across said bars and having means alined with such casting slot adapted to engage the elements on said bars, and means for forcing a bar with its thin end across

such slot independently of said frame whereby a line of assembled matrices may be justified.

8. The combination with a suitable support provided with a transverse casting slot and with oppositely facing abutments adjacent to such slot; of a plurality of laterally tapered matrix bars arranged side by side on said support, adjacent bars bearing similar series of matrices but in reverse order, such matrices terminating short of the thin ends of the bars, whereby any pair of said bars is adapted, when terminally overlapping, to form a space of adjustable width; engaging elements on said bars save 70 at their thin ends; a frame movable across said bars and having means, alined with such casting slot, adapted to engage the elements on said bars, such terminally overlapping bars being thus permitted a limited 75 longitudinal movement; and means for simultaneously forcing together bars thus overlapping, independently of said frame, whereby a line of assembled matrices may be justified. 80

9. The combination with a suitable support provided with a transverse casting slot and with oppositely facing abutments adjacent to such slot; of a plurality of laterally tapered matrix bars arranged side by side on said support, adjacent bars bearing similar series of matrices but in reverse order, such matrices terminating short of such thin ends, whereby any pair of said bars is adapted, when terminally overlapping, to 90 form a space of adjustable width; a frame movable across said bars and having means, alined with such casting slot, adapted to engage said bars save at such thin ends, such terminally overlapping bars being thus 95 permitted a limited longitudinal movement; and two blocks, longitudinally movable on said support, adapted to force together bars thus overlapping, whereby a line of matrices assembled over such casting slot may be 100 justified. 105

10. The combination with a suitable support provided with a transverse casting slot and with oppositely facing abutments adjacent to such slot; of a plurality of laterally tapered matrix bars arranged side by side on said support, adjacent bars bearing similar series of matrices but in reverse order, such matrices terminating short of such thin ends, whereby any pair of said bars are adapted, when terminally overlapping, to form a space of adjustable width; a frame movable across said bars and having a spline alined with such casting slot, said bars having transverse grooves, 115 save at their thin ends, adapted to be engaged by said spline, such terminally overlapping bars being thus permitted a limited longitudinal movement; and means for simultaneously forcing together bars thus 120 125 130

overlapping, whereby a line of assembled matrices may be justified.

11. The combination with a suitable support provided with a transverse casting slot 5 and with oppositely facing abutments adjacent to such slot; of a plurality of laterally tapered matrix bars arranged side by side on said support, adjacent bars bearing similar series of matrices but in reverse order, such matrices terminating short of such thin ends, whereby any pair of said bars are adapted, when terminally overlapping, to form a space of adjustable width; a frame movable across said bars and having

15 a spline alined with said casting slot, said bars having transverse grooves, save at their thin ends, adapted to be engaged by said spline, such terminally overlapping bars being thus permitted a limited longitudinal movement; and two blocks, longitudinally movable on said support, adapted to force together bars thus overlapping, whereby a line of matrices assembled over such casting slot may be justified.

25 12. The combination with a suitable support provided with a transverse casting slot and with oppositely facing abutments adjacent to such slot; of a plurality of laterally tapered matrix bars arranged side by side on said support, adjacent bars bearing similar series of matrices but in reverse order, such matrices terminating short of such thin ends, whereby any pair of said bars are adapted, when terminally overlapping, to 30 form a space of adjustable width; a frame movable across said bars and having splines alined with such casting slot and adapted to engage said bars, the latter having transverse grooves for this purpose save at their thin ends, which are cut away so as to permit terminally overlapping bars a limited longitudinal movement; two blocks longitudinally movable on said support adapted to force together bars thus overlapping, whereby 45 a line of matrices assembled over such casting slot may be justified; and means adapted to simultaneously actuate said blocks.

13. The combination of a plurality of laterally tapered matrix bars arranged side by side, adjacent bars having their thin ends oppositely directed and bearing similar series of characters but in reverse order, such matrices terminating short of such thin ends, whereby the latter are left blank and any bar is adapted to form a blank space of adjustable width on a line transversely of said bars; and means adapted to be detachably connected with selected bars to force 55 such bars inwardly a variable amount under pressure, whereby a line of assembled matrices may be justified, or to withdraw such bars, as desired.

14. The combination of a plurality of laterally tapered matrix bars arranged side by

side, adjacent bars having their thin ends oppositely directed and bearing similar series of characters but in reverse order, such matrices terminating short of such thin ends, whereby the latter are left blank, any pair of bars being movable to cause their thin ends to overlap and thus form a blank space of adjustable width on a line transversely of said bars; and means adapted to be detachably connected with bars thus overlapping to force such bars inwardly a variable amount under pressure, whereby an assembled line of matrices may be justified, or to withdraw such bars, as desired.

15. The combination with a suitable support provided with a transverse casting slot and with oppositely facing abutments adjacent to such slot; of a plurality of laterally tapered matrix bars arranged side by side on said support, adjacent bars bearing similar series of matrices but in reverse order, such matrices terminating short of such thin ends, whereby any pair of said bars are adapted, when terminally overlapping, to form a space of adjustable width; engaging elements on said bars save at their thin ends; a frame movable across said bars and having means, alined with such casting slot, adapted to engage the elements on said bars, such terminally overlapping bars being thus permitted a limited longitudinal movement; and means adapted to be detachably connected with bars thus overlapping to force such bars inwardly, whereby an assembled line of matrices may be justified, or to withdraw such bars, as desired.

16. The combination with a suitable support provided with a transverse casting slot and with oppositely facing abutments adjacent to such slot; of a plurality of laterally tapered matrix bars arranged side by side on said support, adjacent bars bearing similar series of matrices but in reverse order, such matrices terminating short of such thin ends, whereby any pair of said bars are adapted, when terminally overlapping, to form a space of adjustable width; engaging elements on said bars save at their thin ends; a frame movable across said bars and having means, alined with such casting slot, adapted to engage the elements on said bars, such terminally overlapping bars being thus permitted a limited longitudinal movement; and two blocks, longitudinally movable on said support, adapted to be detachably connected with bars thus overlapping to force such bars inwardly, whereby an assembled line of matrices may be justified, or to withdraw such bars, as desired.

17. The combination of two or more laterally tapered matrix bars arranged side by side, adjacent bars having their thin ends oppositely directed and bearing similar series of matrices, but in reverse order, such matrices terminating short of such thin

ends, whereby the latter are left blank; means adapted to secure said bars with selected matrices in alinement, the thin ends of said bars being formed so as to be unaffected by said securing means, whereby such end of any bar is adapted to be moved independently of said securing means to form a blank space of adjustable width in such line of matrices, said bars also bearing 10 blanks interposed between such matrices.

18. The combination of two or more laterally tapered matrix bars arranged side by side, adjacent bars having their thin ends oppositely directed and bearing similar series of matrices, but in reverse order, said bars also bearing blanks interposed between such matrices and such blanks being so arranged that those on adjacent bars register with each other when the bars are brought 20 up with their ends even.

19. The combination of two or more laterally tapered matrix bars arranged side by side, adjacent bars having their thin ends oppositely directed and bearing similar series of matrices, but in reverse order, such matrices terminating short of such thin ends, whereby the latter are left blank and any bar is adapted to form a space of adjustable width on a line transversely of said 25 bars, said bars also bearing blanks interposed between such matrices and such blanks being so arranged that those on adjacent bars register with each other when the bars are brought up with their ends even.

20. The combination of two or more laterally tapered matrix bars arranged side by side, adjacent bars having their thin ends

oppositely directed and bearing similar series of matrices, but in reverse order, such matrices terminating short of such thin ends, whereby the latter are left blank and any bar is adapted to form a space of adjustable width on a line transversely of said bars, said bars also bearing blanks interposed between such matrices and such blanks being so arranged that those on adjacent bars register with each other when the bars are brought up with their ends even; and means for forcing a bar with its thin end across such line, whereby a line of assembled 50 matrices may be justified.

21. The combination of two or more laterally tapered matrix bars arranged side by side, adjacent bars having their thin ends oppositely directed and bearing similar series of matrices, but in reverse order, such matrices terminating short of such thin ends, whereby the latter are left blank and are adapted, when terminally overlapping, to form a space of adjustable width; said 55 bars also bearing blanks interposed between such matrices and such blanks being so arranged that those on adjacent bars register with each other when the bars are brought up with their ends even; and means for simultaneously forcing together bars with their thin ends thus overlapping, whereby a line of assembled matrices may be justified.

Signed by me this 12th day of August, 1910.

WILLIAM A. READE.
